UNITED STATES PATENT OFFICE.

EDWIN I. GOLDING, OF NEW YORK, N. Y.

DESIGN FOR A TEXTILE FABRIC.

Application filed May 6, 1924. Serial No. 9,498. Term of patent 3½ years.

To all whom it may concern:

Be it known that I, EDWIN I. GOLDING, a citizen of the United States, and a resident of 420 Riverside Drive, in the city, county, and State of New York, have invented a new, original, and ornamental Design for a Textile Fabric, of which the following is a specification, reference being had to the accompanying drawing, forming part of this specification.

The figure is a plan view of a piece of fabric embodying my design.

I claim:

The ornamental design for a textile fabric as shown.

In witness whereof, I have hereunto signed my name this 25th day of April, 1924.

EDWIN I. GOLDING.
